FISH AQUARIUM

Robert B. Lee, 7400 Sportman Drive,
Falls Church, Va. 22043

Filed Mar. 26, 1969, Ser. No. 16,464

Term of patent 14 years

Int. Cl. D30—01

U.S. Cl. D30—6

FIG. 4

FIG. 5

FIG. 6

FIG. 1 is a front elevation of a fish aquarium showing my new design;

FIG. 2 is a top plan view of FIG. 1;

FIG. 3 is a bottom plan of FIG. 1;

FIG. 4 is an end elevation looking from the right of FIG. 1;

FIG. 5 is an end elevation looking from the left of FIG. 1; and

FIG. 6 is a cross section taken along line 6—6 of FIG. 1 and being cross hatched to indicate a transparent material, such as glass, plexiglass, etc.

I claim:

The ornamental design for a fish aquarium, substantially as shown and described.
